UNITED STATES PATENT OFFICE

1,994,637

FURNACE LINING AND METHOD OF
PREPARING SAME FOR USE

George F. Doyle, Elmhurst, Ill., assignor to S. Obermayer Company, Chicago, Ill., a corporation of Ohio

Application April 25, 1931, Serial No. 532,855

4 Claims. (Cl. 25—157)

This invention relates to improvements in plastic furnace linings, and more particularly to a new and novel method of preparing plastic substantially monolithic furnace lining for use, the invention being highly desirable for the lining of the walls of practically any kind of combustion chamber, lining conduits for hot fluids or flames, etc., although the invention may have many and various uses and purposes as will be apparent to one skilled in the art.

In the past, in an endeavor to improve upon the original fire-brick lining for furnaces, fire boxes, or other combustion chambers, a lining of refractory plastic material, such as a compound of which the major ingredients were a suitable clay and crushed fire-brick or the equivalents, was frequently used, since with such material a substantially monolithic lining could be produced which did not possess the open voids and interstices of the old fire-brick construction. Difficulty, however, has been experienced in the provision of such a lining with an efficient and expeditious method of installation.

Perhaps the most common method of providing a suitable plastic monolithic lining included the laying of courses of blocks or chunks of the plastic material within the combustion chamber, and the hand-hammering with a suitable mallet or rammer of each course to thereby unite the chunks of one course with each other and each succeeding course with the preceding one, so that substantially a one-piece lining would result. Due to the obviously objectionable process of hand-hammering, power ramming was adopted with the utilization of a hydraulic or air rammer and with the resulting more economical and expeditious installation. Of course, in the latter of these installations, namely, with the use of the power rammer, and quite frequently in the hand-ramming method, an endeavor was made to compensate or allow for the expansion of the lining. To this end, light wooden boards or strips of asbestos were inserted in the lining, especially at the corners, the idea being that the wooden boards would burn out and leave an expansion gap, while with asbestos the natural compressibility thereof would allow for expansion. However, it was soon learned that the wooden boards would not burn out until the lining had completely vitrified under a very high temperature and the damage, such as cracking, bulging, spalling, or the like, had already occurred; and the asbestos joints filled with dirt very quickly and would not allow the proper expansion.

It was also learned that the hand rammed lin-

ings were more satisfactory than the power rammed linings. Quite frequently hand rammed linings remained in use for a relatively great length of time, while the power rammed linings in nearly every instance had to be reinstalled. This was due to the fact that with hand ramming, while a seemingly monolithic lining was produced, in reality the lining varied in a most irregular fashion in degrees of density, so that upon the application of high temperatures, the expansion of the denser portions in the lining would be taken up by those of less density.

On the other hand, power ramming resulted in a monolithic lining which was nearly homogeneous and consequently expanded as an entirety whereupon spalling, cracking and the like occurred with far greater frequency than with a hand rammed lining. It should also be borne in mind that with the hand rammed lining, there was no definite way of determining just which lining would last and which lining would not, these linings being in addition subject to shrinkage cracks and small ruptures.

The present invention has been designed to overcome the above noted as well as other defects and objections in the provision of a hot chamber lining installed in such a manner that the lining may freely contract and expand while in use with a negligible danger of spalling, cracking, bulging, or similar injuries occurring.

It is also an object of this invention to provide a new method of installing or preparing for use a plastic monolithic furnace lining, the method permitting the use of a power rammer with no injurious results after vitrification.

Another object of this invention is the provision of a method of installing or preparing for use a monolithic lining for hot chambers, which method eliminates the use of any other material than that forming the lining and leaves the lining before and after vitrification free to expand and contract in accordance with temperature variations.

It is another object of this invention to provide a method of installing a true monolithic lining for hot chambers, wherein there are no separation gaps in the lining even at bridge walls or in places of like character, and the lining being free to expand and contract in accordance with temperature variations.

Still another object of this invention is the provision of a furnace or other hot chamber lining which eliminates shrinkage cracks by concentrating the shrinkage at joints, eliminates spalling by giving the material room to expand, and greatly lengthens the life of the lining by eliminating

small interior or substantially invisible ruptures, and which lining may be installed in an easy and very economical manner.

A still further object of this invention is the provision of a plastic monolithic furnace lining which may be easily installed and compacted to a high degree, which may be easily vitrified, and which does not result in injury due to expansion and contraction before or after vitrification.

10 While some of the more salient features, characteristics and advantages of a lining and method embodying this invention have been above pointed out, others will become apparent from the following disclosures.

15 The invention includes these and other features of construction and a method of installation or preparation for use hereinafter described, and shown in a preferred manner and form in the drawings, which are deemed desirable for the purpose of more clearly setting forth the invention, as more particularly indicated by the claims.

On the drawings:

Figure 1 is a vertical sectional view through a furnace lined with plastic material in accordance with the principles of the present invention, the section being taken looking toward the furnace door.

Figure 2 is a transverse vertical sectional view through the structure shown in Figure 1.

30 Figure 3 is a fragmentary plan sectional view taken substantially as indicated by the line III-III of Figure 2, and illustrating an early step in the installation of the lining.

35 Figure 4 is a view similar to Figure 3 and illustrating a further step in the installation of the lining.

Figure 5 is a view similar to Figures 3 and 4, and showing a further step in the installation and the preparation for use of the lining.

40 Figure 6 is an enlarged fragmentary sectional view illustrating the manner in which the furnace lining is anchored to the wall.

As shown on the drawings:

45 In the drawings selected for the purpose of rendering the present invention more clear, there is shown a furnace which includes the customary brick wall 10, grate 11, and ash pit 12 there beneath, and boiler 13.

50 The interior of the furnace is lined with a plastic monolithic lining 14 of any material suitable for the purpose, and immediately to the rear of the ash pit 12 a bridge wall 15 of the same lining material is provided in a manner to be later described herein and whereby the bridge wall 55 may, if so desired, be rendered a substantially integral part of the rest of the lining, there being no need of a severance of the bridge wall from the lining on the side walls.

55 As seen more clearly in Figures 2 and 5, the lining is provided at spaced intervals with grooves or joints 16 extending inwardly substantially normally to the lining between the corners, and obliquely at the corners. These grooves which, it will be noted, preferably, although not necessarily, do not extend entirely through the lining but to a depth in excess of one-half the thickness of the lining, permit the lining to expand and contract in accordance with temperature variations freely and with practically no danger of resulting spalling, cracking, bulging, rupturing or similar injuries. In fact, in some instances, these grooves or joints will be substantially closed when the furnace is in operation, and open up or spread when the furnace is cool. Consequently, the 70 grooves are kept clean throughout the life of the

lining and are not subject to dirt accumulation as is an asbestos or similar filler. Furthermore, the lining may freely expand and contract during vitrification as well as subsequently thereto, so that the wall is not dependent upon any severe heat treatments before it is capable of functioning properly.

With reference now to Figures 3 to 6 inclusive, my new method of installation and preparation for use of the lining will be exemplified. At the 10 outset, at suitable intervals, expansion bolt anchors 17, or any other suitable form of anchoring device, are engaged in the wall 10 of the furnace and securely locked in position. Each of the anchors carries a relatively broad head 18 thereon around which the plastic material is rammed in a manner to completely cover the head of the anchor. The plastic material, which is preferably of the consistency of a reasonably stiff putty, is laid in courses in blocks or chunks 19 (Figure 3) 15 and repeated application of power rammers effectively unite the respective blocks and subsequently the respective courses into a homogeneous monolithic mass or one-piece lining 14. As seen in Figure 4, the bridge wall 15 forms an integral part of the lining 14 on the main wall 10, as do all other peculiar formations that may be required.

20 After the entire lining is rendered substantially homogeneous in consistency, and while still plastic, a suitable power driven chisel is utilized for the purpose of cutting the grooves 16 which, as pointed out hereinabove, extend inwardly a distance preferably in excess of one half the thickness of the lining, or even entirely through the lining. The grooves or joints are placed at intervals found most suitable, and when deemed necessary a transversely extending groove or joint may be employed, as seen in the central part of Figure 2. After the cutting of the grooves, the lining may be either left open for a period of time to an initial air drying process, or be subjected to a relatively moderate heat treatment for a lesser period of time. In either instance, the lining is subsequently vitrified by using the furnace in the customary manner, the first heating of the furnace to its relatively high temperature resulting in an effective vitrification of the lining.

25 It will be noted that a lining installed and prepared for use by the above method will be much more compact than the old hand rammed lining, 30 it being necessary in most instances to use several more pounds of material per cubic foot of lining than is used with hand ramming. Consequently, a different and more difficult problem relative to expansion and contraction of the lining is presented, for the lining expands and contracts in homogeneous units of substantially uniform compactness, and not in an irregular manner as where the lining varies considerably in density as the result of hand ramming. As pointed out hereinabove, this problem cannot be solved by defining wall sections with strips of some combustible or compressible filler, nor by any of the other methods heretofore used; but it is to be clearly noted that both during and after vitrification of the 35 lining, the grooves or joints 16 provide adequate allowance for the expansion of the lining in relatively large homogeneous units, and shrinkage cracks are eliminated due to the fact that the shrinkage is concentrated at the joints. The mass being rendered homogeneous by power ramming, small ruptures and breakages of an injurious character, either visible at the surface, or in the interior of the material are non-occurred.

40 From the foregoing, it is apparent that I have 35

provided a plastic monolithic furnace lining installable by a new and novel method which permits the use of power ramming means or other expeditious equivalents, lessens the labor and cost of installation and preparation for use, effectively prevents spalling, bulging, cracking, ruptures and similar injuries, eliminates the use of foreign material in the establishment of joints, and adequately allows for expansion and contraction. It will furthermore be noted that repairs, replacements, alterations, and individual or peculiarly shaped structures may be made more expeditiously and economically in accordance with the principles of the present invention than with methods and means known heretofore.

I am aware that many changes may be made and various details of the method varied through a wide range without departing from the principles of this invention, and I, therefore, do not pur- pose limiting the patent granted hereon, other- wise than is necessitated by the prior art.

I claim as my invention:

1. The method of preparing a furnace lining for use, consisting of applying plastic material and highly compacting the same until substantially a monolithic lining is formed, then cutting continuous grooves in said lining substantially normal thereto to a depth in excess of half the thickness of said lining at spaced intervals between corners, cutting like grooves obliquely at corners, leaving said grooves empty, and hardening said lining.

2. A monolithic plastic furnace lining for ex- tending around the lined parts of a furnace and

having spaced empty continuous grooves therein arranged to divide the lining into unitary expansion sections, said grooves being of such a size and depth to permit an initial shrinkage of said lining when first drying out and then a relative over ex- pansion when the lining is initially hardened by the application of heat, and said sections subse- quently expanding and contracting with tempera- ture changes during the use of the furnace, the grooves opening and closing proportionally.

3. A method of installing a monolithic furnace lining of plastic refractory material which consists in ramming the material into place and thereby compressing it to a substantially uniform density and forming in the fire receiving face thereof a plurality of elongated narrow grooves of a depth slightly less than the thickness of the lining and keeping said grooves open and exposed to the furnace atmosphere while hardening and vitrifying the lining.

4. A method of installing a monolithic furnace lining of plastic refractory material which consists in ramming the material into place and thereby compressing it to a substantially uniform density and cutting out and removing narrow sections of the material to form in the fire receiv- ing face thereof a plurality of elongated narrow grooves of a depth slightly less than the thickness of the lining, and keeping said grooves open and exposed to the furnace atmosphere while hard- 30
